UNITED STATES PATENT OFFICE

2,514,372

FUEL BURNING SPACE HEATER WITH
REFLECTOR MEANS

William G. Carter, Monrovia, Calif., assignor to
Affiliated Gas Equipment, Inc., Cleveland, Ohio,
a corporation of Delaware

Application August 26, 1949, Serial No. 112,548

7 Claims. (Cl. 126—91)

1

This invention relates to space heaters and particularly to a heater for installation in the wall of a room.

An object of the invention is to provide a vertical type vented gas heater delivering heat primarily by radiation and secondarily by convection, mountable within a building wall and without any substantial protrusion into the room, of relatively inexpensive construction, and economical in operation.

A more particular object is to provide a body height heater of the character described whereby heat will radiate and be reflected throughout the strata where heat is most required.

Another object is to provide a high safety factor in a heater of the character described wherein open flame is avoided, and downdraft conditions are provided for.

Another object of the invention is to provide a new and improved space heater construction employing a special form of heating element comprising an elongated tube with a central partition, the tube having indentations which cooperate with the partition to restrict the passage of products of combustion rising through the tube, thereby capturing the heat more effectively and radiating a high percentage of the heat generated which otherwise would escape through the vent.

Another object is the provision of a panel type heater employing a gas heating element and adapted to fill a cut in a wall between two rooms and supply heat to both rooms.

Still another object of the invention is to provide a new and improved space heater wherein a single heating tube may be utilized with more than one reflector, each reflector facing in a different direction so as to throw the heat in corresponding directions into different rooms, and to provide a single control for gas used in the heating element which may be manipulated from different sides of the apparatus.

A further object of the invention is to provide a new and improved space heater featuring a single gas fired heating element disposed so as to supply heat from a common source for dispersion by oppositely directed reflectors wherein the reflectors are so arranged with relation to the heating element that unequal quantities of heat may be reflected in the respective directions which the reflectors face.

With these and other objects in view, the invention consists in the construction, arrangement and combination of the various parts of the device whereby the objects contemplated are attained, as hereinafter more fully set forth, pointed

2

out in the claims and illustrated in the accompanying drawings, in which:

Figure 1 is a front elevation of my heater, said heater having the same appearance on the opposite side.

Figure 2 is a side elevation of the heater shown as installed in a wall.

Figure 3 is a vertical section of the heater taken on the line 3—3 of Figure 1 and shown as installed in a wall.

Figure 4 is a diagrammatic plan illustrating a dual valve control for the heater which can be selectively operated from either side of a wall.

Figure 5 is an enlarged front elevation of the heater with trim and cover parts removed.

Figure 6 is a cross section taken on the line 6—6 of Figure 3.

Figure 7 is a perspective exploded view of heating element and reflector parts.

Figure 8 is a cross section similar to Figure 6 but illustrating a different form of construction wherein, among other things, the oppositely facing reflectors disperse unequal volumes of heat.

Figure 9 is a vertical section similar to the lower end portion of Figure 3, but illustrating a different form of burner chamber including a shelf separating the burner chamber from the reflecting chambers.

Figure 10 is a perspective view taken on the line 10—10 of Figure 9.

30. This application is a continuation in part of my copending application Serial No. 717,775, filed December 21, 1946, which was a division of my copending application Serial No. 549,542, filed August 15, 1944 now Patent No. 2,487,775 dated November 8, 1949.

In Figures 1 to 7 are illustrated a form of the device wherein a single heating element 20 serves two rooms on opposite sides of a wall W by means of a back-to-back reflector 21. In this case the tube of the heating element and the reflector may be economically and satisfactorily made integral, as for example, by forming the tube in two hemi-cylindrical members 22 and extending the tube walls into reflector wings 23. These wings may be formed with flanges 24 for securing to vertical side plates 25 with inturned flanges 26a of frame moldings 26 inserted between the wing flanges and the side plates. The tube sections can be welded together along the lines 27 where the hemi-cylinders meet. The plates 25 serve as structural frame members and also for protection for the studding S of the wall. Of course, the reflector elements can be made separately and attached to a unitary heating tube or be

mounted so that the inner edges are in proximity therewith.

Figure 8 illustrates a single heating element 30 with back-to-back reflectors 31 and 32 affording delivery of a greater amount of heat from one side than from the other, a heater particularly useful where a small room is located on one side of the wall W and a larger room on the other side.

The reflectors may be made in sections 33, 10 as shown, with a distorted V cross-section and welded at 34 along the heating element tube, although such attachment is not essential. The form of reflector provides for a relatively small arc of the tube circumference to be exposed on the side of the reflector 31 and a relatively large arc to be exposed on the side of the reflector 32, whereby less heat is delivered from the reflector 31 and greater heat from the reflector 32. The reflecting area available on the reflectors will ordinarily be greater on the side wherein the greater portion of the tube is exposed than on the other side.

I also show here a gas valve 35 which may be provided with dual control stems and handles 36, whereby the heater may be turned on or off from either side and, therefore, from either room. This feature may be employed in either form of gas heater shown.

The form of the invention illustrated in Figures 1 to 7 features, in particular, the utilization of no more than two members herein designated by the reference character 22 which may be separately formed and made identical before being placed back-to-back and welded along the lines 27. The form of the device there shown lends itself to a relatively inexpensive construction and reduces the number of parts to a material extent without in any way detracting from efficient performance of the device.

In the form illustrated in Figure 8 much the same principle of inexpensive construction is followed as has been noted in connection with Figures 1 to 7, with the exception that the heating element may be separately formed and thereafter welded to the reflectors which are made in complementary parts. Obviously, the relative sizes of the reflectors 31 and 32 may be varied to a considerable extent so that the heat may be reflected in equal proportions or in proportions wherein but a minor portion is distributed into one room permitting the remainder to be distributed into a room on the opposite side. In an arrangement of the kind illustrated in Figure 8 the room areas to be heated may be considerably disproportionate and the heater so designed that temperatures in the different rooms are substantially equalized.

The foregoing description is taken in substance from my said co-pending applications Serial No. 717,775 and Serial No. 549,542.

In more detail, the heater of this application comprises the hollow heating element 20, preferably, although not necessarily comprising a tube having opposite staggered indentations 40 and 41, with straight side walls 42 and 43, and a vertical internal baffle 44. This heating element is preferably about body height. Whether made according to the illustrations in Figures 6 or 8, it constitutes an embodiment of the device patented in my U. S. Patent No. 1,991,788, granted February 19, 1935. While this type of tubular heating element is preferred, the present invention is not limited to such, and may embody other forms of vertically elongated hollow heating elements 75.

wherein heat from products of combustion is radiated outwardly.

Below the heating element, which is open at the lower end, is a gas burner 45 adaptable for consuming any desired natural, artificial or "bottled" gas. The burner 45 is controlled by the valve 35 from a gas supply 46. A pilot 45a is associated with the burner 45.

The burner is located in a burner chamber 47 (Figure 3) or 47' (Figure 9).

The chamber 47 is formed by a cylindrical enclosure 48 secured to the lower end of the heating element by a collar 49. The enclosure 48 is accommodated in suitable cut-outs 55 in the members 22, and is supported by cooperating brackets 56 which are secured together as by screws 57 in clamping engagement with the enclosure 48. The brackets may be secured to the flanges on reflector members 22 as by screws 58.

In the form of Figure 9, the burner chamber is defined by downward extensions 50 of the reflector elements, closed off at the top by a shelf 51 provided with an opening 52 receiving the heating element, and closed off at front and rear by removable plates 53 and 54. In all forms, the burner chamber is open at the bottom.

In all forms, at the upper end of the heating element and reflector is a shelf 60, this shelf closing off the upper end of reflector chambers 61 and 62. This shelf 60 has an aperture 59 receiving the upper end of the heating element. In the form employing the lower shelf 51, the latter closes off the lower end of said reflector chamber.

The upper end of the heating element 20 may be restricted by a cap 65, and built around and above the cap is a collector box and downdraft assembly 66.

This assembly comprises side walls 67 rising from the shelf 60, and a canopy 68 adjoining the upper edges of the side walls. The canopy may include twin hollow members 69 as illustrated, such construction contributing a desired contour, firmness, and heat insulating properties. Centrally of the canopy 68 is an outlet 70 which is adapted to be connected to a wall vent 71. A thermal insulation pack 72 preferably surrounds the collar 70. The side walls 67 and canopy 68 may be supported, at least in part, by horizontal brackets 73 attached to the side plates 25.

Directly below, and spaced from the lower end of the collar 70 and above the cap 65, is a spreader 74, which may be, although not necessarily, a continuation of the vertical baffle 44.

The heating element, reflectors, and superstructure which includes the collector box and downdraft assembly, may be supported on any suitable frame piece, as for example feet 75 extending down to floor level from the side plates 25.

The functional parts can be installed in a cut 60 through a building wall, and the frame molding 26 put into place for purposes of trim. Upper louvered face plates 80 and lower louvered face plates 81, are preferably utilized to complete the trim, and a protective grill 82 is put into place over the front of the reflector chamber.

In Figure 4, a single gas supply 46 is shown divided into two branches 46', both connected with the burner, and both being provided with valves 35', controllable on opposite sides of the wall W, by which the gas can be turned on from either side of the wall, but must be turned off from the same side it was turned on. This is merely an alternative to the single valve with dual controls, and while probably not as preferable, is included as a possible modification.

In operation of any form of the heater other than with the control shown in Figure 4, assuming that the pilot 45a is burning, valve 35 can be opened from either side by one of the handles 36, and burner 45 will deliver hot gases to the heating tube or element 20. In passing upwardly, these gases heat the tube. Some of this heat passes by radiation directly into the area to be heated, and some of the heat rays strike the surfaces of the reflectors and are reflected into the room. Gases passing upwardly through the cap 65 are diverted around the spreader 74 and then enter the outlet collar 70 from whence they are vented to atmosphere. Under downdraft condition, the downdraft strikes the cup shaped upper surface of the spreader, and passes laterally out through the louvers of the upper plate 80.

The heat emitted is primarily in the form of infra-red rays, dispersed into the area heated over a body height stratum.

Although I have herein shown and described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent structures.

For example, the form of fabrication illustrated in Figure 7 may be employed in constructing a heater with equal opposite heat dispersion (Figure 6) or with unequal dispersion (Figure 8). On the other hand, the fabrication illustrated in Figure 8 may be employed in building a heater of equal heat distribution. Nor is the invention limited to either form of fabrication, as the principles explained may be embodied in various modifications of construction. The particular superstructure illustrated is not essential, as other gas collecting means, with or without a downdraft assembly (depending on conditions) may be employed. The heating element will operate, although less efficiently, without a baffle or indentations. It is desirable, although not essential, to incorporate some form of partial obstruction therein, to impede the upward flow of products of combustion, and thus gain more value from the hot gases passing upwardly. The heating element may be substantially cylindrical, as shown, or have an oblong or rectangular cross section, and may be subdivided if desired, into two or more sections.

Thus the principle could be embodied in a structure having a wide heating element, single or multiple, so long as the extreme side walls are adapted to be connected to, or lie contiguous to, the inner edges of reflector wings. These wings are preferably either an extension of, or joined to, the heating element, but if their inner edges lie contiguous to the heating element, such constitutes an embodiment of the invention.

The frame may vary in detail, the side plates thereof being separate parts, as illustrated, or being fabricated with an adjacently positioned part. For illustration only, and not by way of limitation, the frame shown comprises the side plates 25 and the supporting legs 75. The side plates perform the dual function of retaining the reflector and heating element assembly, and protecting the adjacent wall structure from excessive heat. These plates need not be in a form to offer heat protection, if some other protective element is employed, or if, for any reason, heat protection is not needed.

Having described my invention, what I claim as new and desire to secure by Letters Patent is:

1. A space heater adapted for installation in an aperture through a building wall to project heat into the spaces on opposite sides of said wall comprising a frame including side plates adapted to be disposed adjacent the edges of said aperture, a hollow heating element having straight sides and an open lower end mounted intermediate said plates, a fuel burner juxtaposed below said heating element adapted to pass products of combustion upwardly through said heating element to thereby heat said heating element, and reflector members at each side of said heating element, the reflector members on each side of the heating element extending outwardly from the straight sides of the heating element along a straight line thereon and terminating substantially contiguous to the edges of the adjacent frame plate, whereby heat radiated from said heating element laterally in the direction of the reflector members is reflected outwardly toward the space to be heated.
2. A space heater adapted for installation in a vertical-edged aperture through a building wall to project heat into the spaces on opposite sides of said wall comprising a frame including side plates adapted to be disposed adjacent the vertical edges of said aperture, a vertical hollow heating element having straight sides mounted intermediate said plates, a fuel burner juxtaposed below said heating element adapted to pass products of combustion through said heating element to thereby heat said heating element, and a pair of curved reflector members at each side of said heating element oppositely and outwardly facing, the reflector members on each side of said heating element extending outwardly from the straight sides of the heating element along a straight vertical line thereon and terminating along vertical lines substantially contiguous to the vertical edges of the adjacent frame plate, the reflector members on opposite sides of said heating element joining said heating element in non-diametrical relation, whereby a larger area of said heating element is exposed to the space on one side of said wall than to the space on the other side of said wall, whereby heat radiated from said heating element laterally in the direction of the reflector members is reflected outwardly toward the space to be heated.

3. A space heater adapted for installation in a vertical-edged aperture through a building wall to project heat into the spaces on opposite sides of said wall comprising a frame including side plates adapted to be disposed adjacent the vertical edges of said aperture, a vertical hollow heating element having substantially straight sides mounted intermediate said plates and aligned with the vertical central portions thereof, a fuel burner juxtaposed below said heating element adapted to pass products of combustion upwardly through said heating element to thereby heat said heating element, and reflector members at each side of said heating element oppositely and outwardly facing, the reflector members on each side of the heating element extending outwardly from the straight sides of the heating element along a straight vertical line thereon and terminating along vertical lines substantially contiguous to the vertical edges of the adjacent frame plate, the vertical line of junction of said reflector members and said heating element on opposite sides of said heating element being in a plane non-diametrical with respect to said heat-

ing element, whereby heat radiated from said heating element laterally in the direction of the reflector members is reflected outwardly toward the space to be heated in unequal amounts.

4. A space heater adapted for installation in an aperture through a building wall to project heat into the spaces on opposite sides of said wall comprising a frame including side plates adapted to be disposed adjacent the edges of said aperture, a vertical hollow heating element having substantially straight sides mounted intermediate said plates, a fuel burner juxtaposed below said heating element adapted to pass products of combustion upwardly through said heating element to thereby heat said heating element, and reflector members approximately vertically co-extensive with said heating element at each side of said heating element oppositely and outwardly facing, the reflector members on each side of the heating element extending outwardly from the straight sides of the heating element along a straight vertical line thereon and terminating along vertical lines substantially contiguous to the vertical edges of the adjacent frame plate, whereby heat radiated from said heating element laterally in the direction of the reflector members is reflected outwardly toward the space to be heated.

5. A space heater adapted for installation in an aperture through a building wall to project heat into the spaces on opposite sides of said wall comprising a supporting means, a hollow heating element mounted in said supporting means, said heating element having straight sides, a lower end having an opening therein, and an upper end provided with a discharge port, a fuel burner juxtaposed below said opening at the lower end of said heating element adapted to pass products of combustion upwardly through said heating element to thereby heat the latter, reflector wings at each side of said heating element, the reflector wings extending outwardly from the straight sides of the heating element along straight lines thereon and shaped to provide in combination oppositely facing concave reflectors vertically intersected by said heating element, whereby heat radiated from said heating element laterally in the direction of the reflectors is reflected outwardly toward the spaces to be heated, and upper and lower horizontal shelves closing off the upper and lower end regions respectively of said reflectors, said heating element extending through both said shelves, said burner being below said lower shelf, said shelves forming with said reflectors reflector chambers separated from the burner at their lower ends and from the heating element discharge port at their upper ends.

6. A space heater adapted for installation in an aperture through a building wall to project heat into the spaces on opposite sides of said wall comprising a frame including side plates adapted to be disposed adjacent the edges of said aperture, a hollow heating element mounted intermediate

said plates, said heating element having straight sides, a lower end having an opening therein, and an upper end provided with a discharge port, a fuel burner juxtaposed below said opening at the lower end of said heating element adapted to pass products of combustion upwardly through said heating element to thereby heat the latter, reflector wings at each side of said heating element, the reflector wings extending outwardly from the straight sides of the heating element along straight lines thereon terminating substantially contiguous to the edges of the adjacent frame plate and shaped to provide in combination oppositely facing concave reflectors vertically intersected by said heating element, whereby heat radiated from said heating element laterally in the direction of the reflectors is reflected outwardly toward the spaces to be heated, and upper and lower horizontal shelves closing off the upper and lower end regions respectively of said reflectors, said heating element extending through both said shelves, said burner being below said lower shelf, said shelves forming with said reflectors reflector chambers separated from the burner at their lower ends and from the heating element discharge port at their upper ends.

7. A space heater adapted for installation in an aperture through a building wall to project heat into the spaces on opposite sides of said wall comprising a supporting means, a hollow heating element mounted in said supporting means, said heating element having straight sides, a lower end having an opening therein, and an upper end provided with a discharge port, a fuel burner juxtaposed below said opening at the lower end of said heating element adapted to pass products of combustion upwardly through said heating element to thereby heat the latter, and reflector wings at each side of said heating element, the reflector wings extending outwardly from the straight sides of the heating element along straight lines thereon and shaped to provide in combination oppositely facing concave reflectors vertically intersected by said heating element, whereby heat radiated from said heating element laterally in the direction of the reflectors is reflected outwardly toward the spaces to be heated.
